UNITED STATES PATENT OFFICE.

GEORGE G. FLOYD, OF CHICAGO, ILLINOIS, ASSIGNOR TO AMERICAN STEEL FOUNDRIES, OF CHICAGO, ILLINOIS, A CORPORATION OF NEW JERSEY.

SIDE-FRAME CONSTRUCTION.

1,378,849.

Specification of Letters Patent. Patented May 24, 1921.

Application filed April 8, 1920. Serial No. 372,221.

To all whom it may concern:

Be it known that I, GEORGE G. FLOYD, a citizen of the United States, residing at Chicago, in the county of Cook and State of Illinois, have invented certain new and useful Improvements in Side-Frame Constructions, of which the following is a specification.

This invention relates to side frames, and particularly to the cast metal type of truck side frame.

In my copending application, Serial No. 344,769, filed December 15, 1919, I have set forth at great length causes and effects of compression, tension and bending stresses set up in a cast metal side frame and which are peculiar to the cast type of side frame. In such case, I disclose a cast metal side frame having pedestal jaws for receiving 20 separate journal boxes.

This present application relates more specifically to a cast metal truck side frame which has no pedestal jaws and which has no integrally-formed journal boxes, but has 25 integrally-formed longitudinally-extending portions at the ends of the frame to which the standard Master Car Builders' journal boxes are bolted. So far as the compression, tension and bending stresses set up in 30 the frame, and the means for overcoming same, are concerned, this application is the same as my copending application above mentioned. Accordingly, no repetition will be made in this application of the subject 35 matter claimed in said copending application, and only such points as are necessary to give a complete understanding of this present invention will be considered.

In my said copending application I have 40 emphasized the value of transmitting forces through the upper web side of the tension member to the compression member by directly connecting the upper web side of the tension member to the compression member 45 instead of transmitting such forces through the journal box jaws or receiving portions. However, in the type of side frame disclosed in this application, some mechanical obstacles are presented in securing the journal 50 boxes to the frame in a manner to meet requirements.

Accordingly, the object of this invention is to provide simple, efficient and reliable means for securing journal boxes to cast 55 metal side frames in which the web of the

tension member is secured directly to the compression member at a point adjacent the fastening or securing means.

This and other objects are accomplished by means of the arrangement disclosed on 60 the accompanying sheet of drawings, in which—

Figure 1 is a fragmentary side elevation of the truck side frame embodying my invention; 65

Fig. 2 is a fragmentary top plan view; and,

Fig. 3 is a fragmentary bottom plan view of the same.

The various novel features of my invention 70 will be apparent from the following description and drawings and will be particularly pointed out in the appended claims.

Referring to the figures of the drawings, it will be noted that I have shown a cast 75 metal side frame having a tension member 10, compression member 11, columns 12 and journal box receiving portions 13 (only one of which is shown), all cast in a single piece. Preferably, as mentioned in my said copending application, the tension and compression members are U-shaped in section and have the webs 14 and 15 thereof at the upper sides of the tension and compression members, respectively, whereby the major 80 portion of said forces transmitted through the tension member may be carried directly to the compression member without passing through the journal box receiving portions, the main object being to avoid the high tension and bending forces specifically considered in said copending application. By having the web 14 of the tension member extend to the web 15 of the compression member, as at the point 16, a mechanical obstacle is encountered in securing the standard Master Car Builders' journal box 17 to the side frame. In other words, the inner bolt 18 which assists in securing a journal box to the side frame, is located at a point 100 substantially directly below the point at which the webs 14 and 15 of the tension and compression members are joined. Accordingly, to set the bolt 18 in its proper place so that it may be passed through the bolt 105 lugs 19 and 20 of the journal box, I have provided the web members 14 and 15 of the tension and compression members with aligned openings 21 and 22, which are sufficiently large to permit the head 23 of the 110

bolt 18 to pass therethrough, whereupon the bolt head may rest upon the upper surface of the journal box receiving flange 24. In this way the inner bolt 18 may be made of the same length as the outer bolt 25, said bolts 18 and 25 in addition to having their heads rest upon the flange 24, extend through the associated journal box lugs and through a tie bar 26, which is secured to a bracket 27 formed integrally with the side frame. The lower ends of the bolts are provided with washers 28 and nuts 29. By making the openings 21 and 22 in the webs of the tension and compression members, respectively, relatively large, it is advisable to compensate for the loss of material. This is done by providing the tension member with enlarged laterally extending flanges 30 which terminate in laterally extending flanges 31 formed on the compression member 11, said flanges being arranged around said openings 21 and 22 and being located over the journal box receiving portion where the webs of the tension and compression members are joined.

By means of this arrangement not only are all of the advantages of overcoming the high tension, compression and bending stresses obtained, but also the journal boxes are secured in place in a simple, efficient and reliable manner.

It is my intention to cover all modifications of the invention falling within the spirit and scope of the following claims.

I claim:

1. In combination, a truck side frame including tension and compression members and a journal box receiving flange all cast in a single piece, the tension and compression members being of channel section with the webs thereof at the upper side of each of said members, respectively, and being joined directly to each other at the journal box receiving portions, a journal box, and inner

and outer bolts for securing said journal box to the side frame, said webs having openings large enough to permit the passage of the bolt head of the inner bolt whereby the inner bolt head may rest upon the journal box receiving flange. 45

2. In combination, a truck side frame including tension and compression members and a journal box receiving flange all cast in a single piece, the tension and compression members having webs connected directly to each other at the journal box receiving portion, a journal box, and inner and outer bolts for securing said journal box to the side frame, said webs having openings large enough to permit passage of the bolt head of the inner bolt whereby the inner bolt head 50 may rest upon the journal box receiving flange. 55

3. A cast metal truck side frame including tension and compression members and a journal box receiving flange all cast in a single piece, the tension and compression members having webs provided with aligned openings to permit the passage of a journal box securing bolt and the head thereof whereby the head of said bolt may rest upon the 60 journal box receiving flange. 65

4. A cast metal truck side frame including tension and compression members and a journal box receiving flange all cast in a single piece, the tension and compression members having webs provided with aligned openings to permit the passage of a journal box securing bolt and the head thereof whereby the head of said bolt may rest upon the 70 journal box receiving flange. 75

Signed at Chicago, Illinois, this 24th day of March, 1920.

GEORGE G. FLOYD.
